UNITED STATES PATENT OFFICE.

EDWARD J. MISSION, OF PITTSBURGH, PENNSYLVANIA, ASSIGNOR TO CENTRAL ELECTRIC TOOL COMPANY, A CORPORATION OF PENNSYLVANIA.

METHOD OF AND MEANS FOR CONTROLLING RECIPROCATING MOTORS.

Application filed March 5, 1924. Serial No. 697,052.

This application is continued in part from application Serial No. 444,520 filed February 12, 1921, relating to electric mechanism, and in part from application Serial No. 527,037, filed January 4, 1922, relating to methods of operating electric tools. 60

My invention relates to electromagnets and means for controlling the same, and particularly to electromagnets comprising a movable element that is employed to do useful work. 65

One object of my invention is to provide an electromagnet that shall constitute a reciprocating electric motor suitable for use as a percussive tool, such as an electric hammer, drill or chipping tool, and that shall automatically regulate the current supplied thereto. 70

Another object of my invention is to provide an electromagnet to do useful work, that shall embody means for regulating the current supplied to the electromagnet in accordance with the operation of the electromagnet. 75

My invention has a particular application to electric hammers, although the principle of control involved is susceptible of application for controlling electromagnets applied to, or employed for other purposes or uses. 80

My invention provides a novel system for controlling a reciprocating motor.

In operating electric hammers of the type in which an electromagnet is periodically energized to reciprocate its core member against a tool or other device to do useful work, current controlling switching devices, such as mechanical vibrators, have been employed, embodying relatively movable contacts. 85

Whether direct current or alternating current energy is used to operate the hammer, it is desirable to control the operation of the switching device in accordance with the operation of the hammer. The switching devices may thus be controlled to operate at optimum instants, that is, at instants beyond which continued energization of the hammer is not desired, or at instants of minimum circuit current, as zero current values 95

when alternating current energy is used. 100

In order to operate a motor of the reciprocating type, it is necessary to supply energy to the motor in the form of impulses. 105

Alternating current energy, which is derivable from the usual commercial light and

power circuit, is adaptable for energizing a reciprocating motor but requires rectification in order that the respective current waves may be supplied to the motor as energy impulses. 60

Switching devices, whether of the motor driven drum type or of the vibrating type, after having been once adjusted, will always operate at the same time, irrespective of external conditions in the circuit controlled by the contacts. 65

When alternating current energy is used, it is desirable to open the circuit at instants of zero current in order to reduce the arcing between contact members. In the usual rectifier there is considerable arcing between the contact members. Such condition is aggravated by the varying inductive reactance in the motor windings caused by the movement of the movable core. When the core moves smoothly in synchronism with the applied energy impulses, the arcing between the contacts is at a minimum, but when the core moves unevenly and leads or lags behind the energy impulses, the arcing is considerably increased. 75

Due to the variations in the impedance of the hammer winding caused by the movement of the core, the contacts would open the circuit of the hammer winding at times when the voltage across the circuit or the current traversing the same would not be zero. Considerable arcing has therefore resulted, interfering with proper operation of the current-controlling device and necessitating a great amount of care and attention to the contacts. Such arcing resulted because the operation of the contacts was effected in response to conditions entirely independent of those obtaining in the circuit controlled by the contacts, instead of in response to conditions obtaining in the circuit controlled by the contacts. 90

It is an object of my invention to control the operation of the contacts of a current controlling device in accordance with and in response to conditions in a circuit controlled by the contacts. Specifically, my object is to control the energization of an electromagnet, particularly such as used as a reciprocating motor, by electric, magnetic or electromagnetic conditions obtaining in the electromagnet or motor. 100

In practicing my invention I employ a reciprocating motor comprising an actuating

110

winding and a movable member responsive thereto, such as a movable core, and provide an auxiliary winding disposed in inductive relation to the actuating winding to be influenced in accordance with the energization of said winding and the movement of the core responsive thereto. The electromotive force induced in the auxiliary winding is a function of the energization of the actuating winding and of the movement of the core and may be utilized to regulate or control an external device that controls the energization of the actuating winding.

In the present application I use an electromagnet arranged to operate as a reciprocating motor to do useful work as a percussive tool, such as an electric hammer, for drilling, chipping, riveting, etc. A switching device, in circuit with the actuating winding, periodically transmits an energy impulse to said winding and establishes a reciprocating movement of the core member in synchronism with the transmitted impulses. By regulating the operation of the switching device in accordance with the electromotive force induced in the auxiliary or secondary winding, the switching device will be controlled in accordance with the operation of the electromagnet or electric hammer. Arcing between contacts of the switching device will thereby be considerably diminished where alternating current energy is used, and the switching device will be operated at the proper time when direct current energy is used.

For a better understanding of the invention, reference may be had to the accompanying drawings in which:

Fig. 1 is a cross-sectional view of an electromagnet designed to operate as a reciprocating motor in accordance with my invention;

Fig. 2 is a sectional view, taken laterally, of the hammer shown in Fig. 1;

Figs. 3 and 4 are respectively, front and bottom views, in elevation, of the magnetic circuit members employed in the hammer shown in Fig. 1;

Figs. 5, 6 and 7 are diagrammatic views of electric circuits for controlling the operation of the hammer in Fig. 1 in accordance with my invention; and

Fig. 8 is a graph illustrating the general form of the current impulses transmitted to the hammer.

As illustrated in Figs. 1 and 2, an electric hammer 10 comprises a main or actuating winding 11, a core member 12 responsive thereto and controlled thereby to do useful work, and an auxiliary or secondary winding 13 disposed adjacent the main winding 11 and the core 12, to be influenced in accordance with the energization of the main winding 11 and the movement of the core

The hammer further comprises a barrel or guide 14, of non-magnetic material, to retain the core in a predetermined path of movement. A plurality of iron laminations 15 are disposed around the main winding 11 and adjacent the barrel 14 to provide a short air gap within which the auxiliary winding 13 is disposed. A front end plate 16 is disposed on and secured to the front end of the barrel 14 and accommodates a cool bushing 17 which holds a tool 18 in the path of travel of the core 12 in its forward movement. A back end plate 19 and handle 20 integral therewith are secured to the rear end of the barrel 14 and cooperate therewith to hold a spring controlled backstop or bumper 21 in position in the path of travel of the core 12 in its backward movement. An enclosing shell or casing 22 surrounds the electromagnet structure and is held in position by the front and the back end plates 16 and 19. A trigger switch 23 is disposed in the handle of the hammer and is subject to control by the operator for initiating and stopping operation of the hammer.

As illustrated in Fig. 2, the laminations are disposed in sets around the barrel 14 and extend radially therefrom. Each set of laminations has an air gap between the ends of the inner laminations 15. All of the air gaps together constitute an annular air gap which is bridged or shunted by the core in its reciprocating movement.

Several of the inner laminations of each set are provided with tips or tenons 24, as illustrated in Figs. 3 and 4, that fit tightly into openings in the barrel 14 and serve to lock the windings in position.

In Fig. 5 energy for operating the hammer 10 is derived from a source of energy which may be a direct or an alternating current circuit 25 and is supplied to the main winding 11 of the hammer through a switching device 26 and a magnet switch 27. The magnet switch is controlled by the trigger switch 23 on the hammer.

The switching device 26 comprises a spring 28, tending normally to hold the switch contacts closed, and a winding 29, operating, when sufficiently energized, to open the switch contacts. The winding 29 is connected to the secondary or auxiliary winding 13 on the hammer and is energized in accordance with the electromotive force induced in the secondary winding 13, to operate the switch 26. A condenser 31 and a blow out coil 32 are provided to diminish arcing between the switch contacts.

When operation of the hammer is desired, the trigger switch 23 is closed. The magnet switch 27 thereupon closes to connect the main hammer winding 11 to the circuit 25 through the switch 26 and the blowout coil 32. The core 12 is thereupon drawn toward

the air gap between the ends of the laminations 15. As the core approaches the air gap, the reluctance of the magnetic circuit of the hammer is considerably and rapidly decreased. In the example illustrated, the core 12 passes the position of minimum air gap length, or passes the position in which it bridges the air gap. The magnetic flux is thereupon quickly increased and a large electro motive force is induced in the secondary winding 13. The winding 29 of the switching device 26, is thereupon sufficiently energized to open the switch contacts against the force of the spring 28. The main hammer winding is thereupon de-energized and the core 12, by reason of its kinetic energy continues its movement until it strikes the tool 18 or the backstop 21, depending upon the direction in which it is travelling. If the core strikes the tool, useful work is done thereby. If the core strikes the backstop, its kinetic energy is stored in the spring of the backstop and restored to the core on its forward stroke.

25 After the core passes the air gap, the switch 26 having been opened to disconnect the main hammer winding, the secondary winding 13 of the hammer is de-energized.

The switch 26 is thereupon immediately reclosed by its spring 28 to reconnect the main winding 11 to the circuit. The core is thereupon again actuated but in the opposite direction and when it substantially shunts the air gap between the ends of the laminations, the switch 26 is again opened to disconnect the main winding from the circuit by reason of the electro motive force induced in the auxiliary winding. The core is thus moved back and forth at a frequency depending upon the frequency of operation of the switching device 26.

The time element of the core and the time element of the switching device 26 should be equal. That is, the time from the instant of maximum voltage in the secondary winding of the hammer, until the core is out of the air gap, must be equal to the time which elapses between opening and reclosing of the contacts of the switching device 26. Such correspondence may be obtained by adjustment of the spring 28 to vary the time element of the switch device.

Reciprocatory motion of the core may thus be obtained by periodically energizing and de-energizing the primary or main winding of the hammer and utilizing the voltage induced in the secondary winding to operate or control a switch or other device for controlling the energization and de-energization of the primary or main winding.

By reason of the inductive relation of the main and the auxiliary windings of the hammer and the magnetic circuits associated therewith, a transformer action exists when the main winding is energized. Only a rela-

tively small electro motive force, however, is induced in the auxiliary winding when the main winding is energized, until the core approaches the air gap. At that time, more efficient transformer action occurs and the induced electro motive force increases rapidly to a large value, which is sufficient to operate the switch 26.

The operation of the hammer constitutes, in effect, a series of operations as an electro magnet. After each operation has been effected the circuit of the operating winding is momentarily opened to de-energize the winding. By means of the electro motive force induced in the auxiliary winding, the hammer automatically indicates the performance of each operation, that is, the movement of the core in one direction or the other. Such induced electro motive force may be utilized for a useful purpose to indicate the operation of the hammer or to regulate its operation, as is herein described, by controlling an external current-transmitting device.

I have disposed the auxiliary winding adjacent the air gap although it may be disposed in other positions in which it will be influenced by the magnetic flux developed by the main winding. In the air gap the auxiliary winding appears to be most responsive to the flux variations effected by the core in its movement.

In Figure 6 a modified circuit is diagrammatically shown, similar to that in Fig. 5, except that a switching device 40, different in design, is employed instead of the switch device 26 of the system in Fig. 5.

The switch device 40, of Fig. 6, comprises in addition to the switch contacts, a holding coil 41, and an operating coil 42. The holding coil 41 is energized from the circuit and is controlled by the magnet switch 27.

The operation of switch 40 is similar to that of switch 26, except that the holding coil 41 restores or closes the switch contacts after each opening of the switch by the operating coil 42 traversed by current induced in winding 13. In the system in Fig. 6 the lag or inertia effect of the spring on switch 26, is obviated.

Normally the holding coil 41 maintains the switch contacts closed. When the core of the hammer approaches the air gap and the secondary winding 13 of the hammer is energized to its maximum degree, the operating coil 42 is energized to open the switch 40 against the pull of coil 41. The main hammer winding and, consequently, the secondary winding are de-energized. The holding coil 41 immediately restores the switch to its closed position, to re-energize the main hammer winding. With each closure of the switch a separate impulse of energy is transmitted to the hammer winding and the core is reciprocated in synchrony.

nism with the impulses. The switch is thus automatically controlled to operate at the proper instant by the auxiliary hammer winding.

5 In Fig. 7 is illustrated another modified system embodying my invention. In this system I employ a mechanical vibrator 50 as the switching device to control the circuit of the main hammer winding. The vibrator 50 comprises a switch member 51, an operating coil 52, a spring 53 and a regulating coil 54. The operating coil 52 is controlled directly by the trigger switch 23.

When the trigger switch 23 is closed the operating coil 52 is energized from an alternating current circuit 55 and together with the spring 53 effects synchronous vibration of the switch member 51. The switch is thus closed for the duration of waves of one polarity and is open for the duration of waves of opposite polarity. The vibrator thus operates as a mechanical rectifier, transmitting all current waves of one polarity but not waves of opposite polarity. The 25 polarity of the transmitted waves will depend upon the polarity of the first wave during which the switch member 51 is closed after closure of the trigger switch 23.

The switch member 51 vibrates in synchronism with the current traversing the operating coil 52, and by adjustment of the spring 53 the travel of the switch member 51 may be reduced to a minimum.

The switch will open and close at instants corresponding to the time when the current value is zero. Having once been adjusted, the switch 51 will open and close when the value of the current in the switch operating coil becomes zero, irrespective of conditions 40 in the circuit of the hammer operating coil controlled by the switch 51.

By reason of the varying inductance of the hammer operating winding 11, caused by the movement of the core 12, the current traversing the hammer winding will not have the same phase relation to the circuit voltage as the current traversing the switch operating winding 52. The switch 51 will therefore open when current traverses the 50 hammer operating winding circuit and arcing at the switch contacts will result.

By means of the regulating switch coil 54, however, the operation of the switch may be regulated in accordance with current conditions in the hammer winding or switch circuit. The operation of the switch may be accelerated or retarded depending upon the movement of the core of the hammer. The switch may thus be controlled to 60 operate at optimum current values when the current traversing the switch will be zero or substantially zero.

The auxiliary winding 13 of the hammer is connected to the regulating coil 54 in such 65 manner that the regulating coil flux bucks

or counteracts the flux of the operating coil 52 of the vibrator or rectifier.

The auxiliary winding 13 on the hammer is energized in accordance with the movement of the core in the hammer. When 70 the core reaches the mid-point of its stroke, adjacent the air gap between the tips of the laminations, the auxiliary winding attains its maximum degree of energization. The regulating coil 54 of the rectifier 50 is thereupon energized to counteract the holding effect of the operating coil 52 and the contacts are disengaged to open the circuit of the main hammer winding 11. The core continues in its movement, however, until 80 it engages the tool 18 or the spring-cushioned stop 21 upon which it expends the energy stored therein by the action of the operating coil.

Alternate current waves are transmitted 85 to the main hammer winding by the rectifier to actuate the core member in the one direction or the other, and the core is permitted to continue its travel after the cessation of each current wave during the intervals between such current waves, to expend its kinetic energy upon the tool or the backstop. The core is thus reciprocated in synchronism with the transmitted current waves at a frequency corresponding to half the frequency 95 of the circuit current.

The oscillogram in Fig. 8 illustrates a typical wave form of current transmitted to the hammer by the rectifier.

The auxiliary winding 13 on the hammer 100 and the regulating winding 54 of the rectifier operate to control the rectifier switch 51 to increase or to diminish the duration of each current wave according to whether the core lags or leads its normal speed. The 105 core is thus kept in step or synchronism with the alternating current in the supply circuit, or with the unidirectional pulsations of current in the main hammer winding. In case the core lags, or is retarded in its operation, the duration of the current wave is extended to increase the magnetic impelling force on the core, and it is brought into step or synchronism. In case the core leads its 110 normal speed, the rectifier switch opening 115 is accelerated to diminish the duration of the current wave and reduce the magnetic impelling force, to keep the core in synchronism.

The operation of the switching device is 120 thus controlled in accordance with the movement and position of the core of the hammer, and the core is automatically kept in step with the current by the operation of the switching device.

I have found that when the auxiliary windings of the hammer and the rectifier are used the necessity for close adjustment of the rectifier is obviated. Without the auxiliary control windings, close adjustment of 125

the rectifier is necessary to reduce the travel of the switch member and consequently, the arcing. This does not mean that the conditions which cause arcing are eliminated, but merely that the extent of separation of the contacts is limited and that the arcing occurs between relatively close contact surfaces. Under such conditions, it is of course impossible to cut off the circuit sharply because of the low resistance of the short arc, and for that reason considerable energy stored in the magnetic field of the hammer is dissipated in the arc as heat, with the consequent deterioration of the contact surfaces.

When the auxiliary windings are employed, however, the rectifier is automatically controlled, notwithstanding a lack of close adjustment, to open the switch at the instant when the current in the switch circuit is a minimum. When the regulating windings are used, the arcing between the rectifier contacts is therefore reduced to a minimum, and excessive deterioration of the contacts is precluded.

My invention, therefore, comprehends broadly a method of controlling the energization of an electromagnet in accordance with its operation, and means responsive to a condition of the electromagnet for controlling an external switching device. Specifically, my invention comprehends a method of and means for controlling the operation of an electric hammer of the reciprocating motor type by regulating or controlling a current transmitting or translating device in circuit with the hammer, in accordance with the operation of the hammer itself.

Although I have shown several systems for controlling the operation of an electric hammer of the reciprocating motor type, modifications may be made therein by the substitution of other current transmitting or translating devices, to control the hammer without departing from the spirit and scope of my invention as set forth in the appended claims.

I claim as my invention—

1. The combination with a source of current and a reciprocating motor energized therefrom comprising a field-producing winding and a magnetizable member actuated thereby with respect to an air gap in the field produced by said winding, of an auxiliary winding inductively related to said first named winding, one of said windings surrounding the other at substantially the region of said air gap, means periodically delivering current from said source to said first named winding, and means controlled by the electro-motive-force induced in said auxiliary winding controlling said current-delivering means.

2. The combination with a source of alter-

nating current and an operating coil, a movable member controlled thereby and a rectifying device embodying relatively movable contact members for supplying to the operating coil predetermined portions of the alternating current, of means responsive to a condition of the coil for controlling the operation of the rectifying device to obviate arcing between the contact members thereof.

3. The combination with a source of alternating current and an operating coil, a movable member controlled thereby and a rectifying device embodying relatively movable contact members for supplying to the operating coil predetermined portions of the alternating current, of means inductively related to the operating coil for controlling the operation of the rectifying device.

4. The combination with a source of alternating current and an operating coil, a movable member controlled thereby and a rectifying device embodying relatively movable contact members for supplying to the operating coil predetermined portions of the alternating current, of means energized in accordance with the position of the movable member for regulating the operating of the rectifying device.

5. The combination with a source of alternating current and an operating coil, a movable member controlled thereby and a rectifying device embodying relatively movable contact members for supplying to the operating coil predetermined portions of the alternating current, of a secondary winding inductively related to the operating coil and influenced by the movable member for regulating the operation of the rectifying device.

6. The combination with a source of alternating current and a main operating coil, a movable member controlled thereby, a rectifying device embodying relatively movable contact members and an operating coil therefor for supplying to the main operating coil predetermined portions of the alternating current, of a secondary coil inductively associated with the main operating coil, a secondary coil inductively associated with the operating coil of the rectifying device, and means connecting both secondary coils in closed circuit relation.

7. The combination with a source of alternating current and an operating coil, a movable member controlled thereby and a rectifying device embodying relatively movable contact members for supplying to the operating coil predetermined portions of the alternating current, and a coil for controlling said contacts, of a secondary coil inductively associated with the main operating coil, and means controlled by the secondary coil for controlling the rectifying device.

8. In a system for operating electric hammers, a source of alternating current, a solenoid, a core reciprocable thereby, a rectifier in

circuit with the source and the solenoid, a second solenoid in which the core reciprocates, and means controlled by current generated in the second solenoid by the movement of the core therein, for regulating the movements of the core.

9. The combination with a source of alternating current and a reciprocating motor comprising a magnetic field having an air gap, a winding for energizing the field, and a magnetic member movable with respect to said air gap to position beyond minimum air gap length, of means effecting delivery of successive unidirectional impulses of current from said source through said winding, an auxiliary winding inductively affected by said first named winding and said magnetic member, and means in circuit with said auxiliary winding for controlling the duration of said current impulses.

10. The combination with a source of alternating current and a reciprocating motor comprising a magnetic field, a winding for energizing the field, and a magnetic member moved thereby, of means intervening between said source and said winding effecting delivery of preponderantly uni-directional impulses therethrough, means for deriving an electro-motive-force dependent upon the current in said winding and the movement of said magnetic member, and means controlling the impulses in said winding in response to said electro-motive-force.

11. The combination with a source of alternating current and a reciprocating motor comprising a magnetic field, a winding for energizing the field, and a magnetic member moved thereby, of means for effecting recti-

fication of current from said source for energizing said winding, means for deriving an electro-motive-force dependent upon the current in said winding and the movement of said magnetic member, and means controlling the rectification in response to said electro-motive-force.

12. The combination with a source of current and a reciprocating motor comprising a magnetic field having an air gap, a winding for energizing the field, and a magnetic member movable with respect to said air gap to position beyond minimum air gap length, of means effecting delivery of successive impulses of current from said source through said winding, an auxiliary winding located adjacent said air gap inductively affected by said first named winding and said magnetic member, and means in circuit with said auxiliary winding for controlling said current impulses.

13. The combination with a source of alternating current and a reciprocating motor, a field winding for said motor and a magnetizable member moved thereby, of inductive means connected to said source while said motor is in operation for controlling the transmission of unidirectional current impulses from said source to said winding, and an auxiliary winding inductively related to said field winding and adapted to react upon said inductive means and thereby modify the duration of said impulses.

In testimony whereof, I have hereunto subscribed my name this 29th day of February, 1924.

EDWARD J. MESSIEN.
